UNITED STATES PATENT OFFICE.

CLAUDE A. LEWIS, OF HOUSTON, TEXAS.

WINDOW-SASH SUPPORT.

Application filed July 11, 1927. Serial No. 204,978.

My invention relates to windows and particularly to the means for mounting and supporting the lower sash therein, so that it can be operated.

6 It is desired that the lower sash be mounted for vertical sliding movement in the casing and also that it be adapted to swing on a pivot to reverse the sash in the frame.

10 In such a window it is an object of the invention to provide a mounting for the sash which is capable of adjustment as to length to adapt it for application to window sashes of different sizes.

15 It is my aim to provide hardware for use on the sash, and rider upon which it is mounted, which will co-act with the window casing to permit the desired movement of the window, and which can be manufactured at a minimum of expense.

20 Referring to the drawing herewith, Fig. 1 illustrates a window casing with the sash thereon equipped with my invention, the casing being in section along one side of the window sash, and the rider of the lower sash being removed. Fig. 2 is a top plan view of the rider employed with the lower sash. Figs. 3 and 4 are front and side views respectively of the rider. Fig. 5 is

25 a perspective view of a guide plate for use on the sash. Fig. 6 is a fragmentary section of the sash and casing showing the use of the guide plate thereon; and Fig. 7 is a broken horizontal section of one of the window jambs showing the rider engaged in the channel thereof. Like numerals of reference are employed to designate like parts in all the views.

30 This application is an improvement upon the structure shown in my co-pending application, Serial No. 154,665, filed December 14th, 1926.

35 In this window the window casing 1 has the window jamb 2 formed to receive an upper sash 3, the lower end of

40 which is equipped with plates 4 on each side thereof, said plates being adapted to rest upon stop plates 5 secured to the side of the jamb. In Fig. 1 the plate 5 is understood

45 as being secured to the portion of the casing which is cut away. It furnishes a support for the plates 4 above and the sash secured thereto. The plate 4 has a forwardly

50 projecting arm 6 thereon with a hooked end 7 presented upwardly to provide a recess 8 to receive a pin upon the lower sash. The plate 5 has its forward end formed with a

rounded recess 9 within which the hooked end 7 of the plate 4 may be supported when the upper end of the sash 3 is swung inwardly.

60 The lower sash 10 is mounted upon riders 11 which are slidable vertically within channels 12 in the window casing.

65 The riders upon which the lower sash is mounted are disclosed in Figs. 2, 3 and 4. They are preferably made of channel iron of approximately U-shape, as shown in Fig. 2, the inner side 13 adjacent the sash being slightly wider than the outward side 14 which fits within the channel 12. The outer 70 side of the rider is open. Within the rider, spaced somewhat from the lower end, is a plate 15, said plate having its upper end secured to one side of the rider and the lower end secured to the opposite side of 75 the rider. The intermediate portion is bent inwardly and the central web, indicated at 15, forms a guide when the rider is moved in the window casing. Within the upper end of the plate is formed an opening 16 to receive a sash cord 17 and the lower end of said plate has a bumper 18 of rubber or other resilient material. This bumper acts as a shock absorber to engage with the stop plate 5 when the rider is moved to its upper 80 limit. It is to be understood that the plates 5 and 6 project into the open side of the rider and in the position spaced above the bumper 18. When the riders are raised, the bumpers 18 will eventually engage with 85 the stop plate 5 and limit the upward movement of the riders. The lower ends of the riders are provided with slots 19 which are formed in an inclined position in the inner 90 wall 13 of the rider, the slots being inclined downwardly and outwardly, as will be noted from Fig. 3.

95 The lower sash 10 has laterally projecting pins 20 at its lower ends which are adapted to fit within the slots 19 in the riders 100 and furnish a pivot upon which the upper end of the sash may be swung inwardly.

105 The upper end of the sash is equipped with a plate 21, the construction of which is best seen from Fig. 5. It has a forward face 22 which is adapted to lie against the forward side of the lower sash, as seen in Fig. 6. The plate is secured to the sash by means of a wood screw 32 engaging through an opening 23 in the plate. Adjacent the upper end of the plate an arm 24 is bent at right angles to the forward side of the plate 110

to lie against the inner side of the sash. This arm has an opening 25 to receive a screw 26. It has an outwardly extending pin 27 thereon, which, when the sash is in its lowered position, is adapted to fit within the notch 8 in the supporting plate 4. The lower end of the plate 21 has a laterally extending arm 29 which fits against the forward side of the rider. At the upper side 10 of the arm 29 a lip 30 is extended outwardly along the side of the sash and inwardly to fit within the channel 12 in the window jamb and act as a guide for the upper end of the sash when the sash is being raised 15 or lowered with the rider in the window casing.

When the sash is moved upwardly with the rider to its upper limit of movement, the bumpers 18 in the riders will engage 20 with the stop members 5 and prevent the riders from further upward movement. In that position the lip 30 will be retained within the channel 12 of the window jamb. A short distance above the lip at that position 25 is a transverse groove 31 in the window jamb. The slot 19 at the lower end of the riders will allow the pins 20 on the lower sash to move upwardly relative to the riders a sufficient distance to bring the lip 30 into 30 registration with the groove 31, as will be understood from Fig. 6. When the sash is thus raised relative to the rider, the lip 30 will register with the groove 31 and the upper end of the sash may be swung forwardly into the room, the sash pivoting on the pins 20 in the slots 19 of the riders at their lower ends. The window sash may be thus swung into reverse position so as 35 to allow access to the outer side of the sash for cleaning or repairing. The window may be returned to its original position by a reverse of this action.

The lip 30 upon the plate 21 will be above 40 the upper end of the rider 11. It need not contact with the rider and it is contemplated that with the lower sash equipped with the plate 21 the riders 11 may be fitted to any 45 length of sash. The riders may be furnished stock sizes but if the rider is too long it 50 may be sawed off to the right length and if the rider is slightly shorter, there will be no material difference for the reason that the upper end of the sash is guided through 55 the action of the lip 30, working within the channel 12, it being obvious that the riders 11 will not necessarily have to be the full length of the sash but only long 60 enough to bear against the arm 29 of the plate. With the lower sash equipped with the plates 21 it will be obvious that the 65 riders and the plates 21 may be furnished to fit with any length of sash whether a common or stock size, or some unusual length of sash, and the window will have the same freedom of movement that it would have

equipped with the form of rider disclosed in my prior application above referred to. The advantages of the invention will be obvious to those skilled in the art.

What I claim as new is:

1. In a window, a casing having longitudinal channels therein, riders in said channels having pin-receiving openings in their lower ends, a sash mounted on said riders, pins at the lower ends of said sash engaging 75 said openings, a plate at each side on said sash above said riders, lateral pins on said plates, lips on said plates extending into said channels, and means to permit said lips to move forwardly out of said channels 80 when said sash is in raised position.

2. In a window, a casing having longitudinal channels therein, riders in said channels having pin-receiving openings in their lower ends, a sash mounted on said riders, pins at the lower ends of said sash engaging 85 said openings, a plate at each side on said sash above said riders, lateral pins on said plates, lips on said plates extending into said channels, and means to limit the upward movement of said riders, the forward side of 90 said channels being grooved to permit said lip to pass and said sash to swing inwardly.

3. In a window, an upper sash, forwardly extending plates thereon, each having an upwardly presented hook thereon, a lower sash, riders thereon slidable in channels in said casing, lower pins on said lower sash extending into slots in said riders, plates on the upper end of said lower sash, pins on 95 said plates adapted to fit within said hooks when said lower sash is closed, and lips on said plates extending into said channels, said lips adapted to be freed of said channels 100 when said lower sash is sufficiently raised.

4. In a window, a casing, an upper sash, forwardly extending plates thereon, each having an upwardly presented hook thereon, a lower sash, riders thereon slidable in channels in said casing, lower pins on said lower 110 sash extending into slots in said riders, plates on the upper end of said lower sash, pins on said plates adapted to fit within said hooks when said lower sash is closed, and lips on said plates extending into said channels, means to limit the upward movement of 115 said riders, said lower sash being adapted to be raised relative to said riders and said lips then freed of said channels.

5. In a window, a casing, an upper sash, forwardly extending plates thereon, each having an upwardly presented hook thereon, a lower sash, riders thereon slidable in channels in said casing, lower pins on said lower sash extending into slots in said riders, 125 plates on the upper end of said lower sash, pins on said plates adapted to fit within said hooks when said lower sash is closed, and lips on said plates extending into said channels, said sash being grooved above said 130

- riders when said riders are in raised position, said lips being adapted to register with said grooves to allow said sash to swing inwardly.
6. In a window, a casing, a lower sash, riders thereon slidable within channels in said casing, a pin and slot connection between said sash and rider at their lower ends, and guide lips on the upper end of said sash projecting into said channels above said riders, said casing being grooved adjacent the upper ends of said channels to allow said guide lips to move free of said channels.
- 10

7. In a window, a casing, a lower sash, 15 riders thereon slidable within channels in said casing, a pin and slot connection between said sash and rider at their lower ends, and guide lips on the upper end of said sash projecting into said channels above 20 said riders, and means to limit the movement of said riders, said lips being free to be moved from said channels when said sash is raised to its upper limit.

In testimony whereof I hereunto affix my 25 signature this 5th day of July, A. D. 1927.

CLAUDE A. LEWIS.
